Patented Sept. 19, 1922.

The diagram illustrates a cash sales book divided into three sections (6, 7, 8) and a flap (10). The sections are labeled 'Clerk's' and 'Voucher' with 'Amount' and 'Price/Amount' columns. The flap is labeled 'Customer's' and 'Check' with 'Amount' and 'Price/Amount' columns. The flap is shown partially open, revealing the sections underneath. A pen is shown resting on the flap.

UNITED STATES PATENT OFFICE.

GEORGE HARTRICK, OF OAK PARK, ILLINOIS, ASSIGNOR TO CARSON, PIRIE, SCOTT AND COMPANY, OF CHICAGO, ILLINOIS.

CASH-SALES BOOK.

Application filed November 27, 1918. Serial No. 264,388.

To all whom it may concern:

Be it known that I, GEORGE HARTRICK, a citizen of the United States, residing at Oak Park, Chicago, in the county of Cook and State of Illinois, have invented certain new and useful Improvements in Cash-Sales Books, of which the following is a specification.

This invention relates to improvements in "cash" sales books.

Heretofore, so far as I am aware, the form of sales books commonly employed in large establishments is one in which a separate sheet of carbon is attached to the book and adapted to be laid in the fold of a long folded sheet containing the necessary or desirable blanks, voucher and check number, with headings or designations for indicating the name of the purchaser, residence, month, year, amount received, price, amount of sale, quantity of articles, etc., the folded sheets having the intelligence duplicated thereon, the markings appearing on the upper faces of the top and bottom sheets, so that writings on the top sheets will be recorded directly on the top sheet, and through the carbon sheet transferred to the bottom sheet, the sheets being perforated at their lower ends for ready separation, the bottom or lower sheet being detachably secured to the short sections of the binding of the book.

The book thus generally described answers and is used for substantially the same purposes as the one about to be described, but involves more labor and expense of time than the present book, in that it is necessary for the clerk to first fold back the top sheet and bring the carbon to position between the folds and after making the necessary record, the carbon is again taken out or lifted and held back out of the way, when the clerk must separate the vouchers by two tearing operations into two vouchers or checks, one of which is placed in the package with the purchase, and another (a duplicate of the one placed in the package) "goes to the cashier" and becomes the "cashier's voucher" after having had torn from it a check or voucher which is returned with the change to the sales clerk, which voucher or check bears numbers and markings corresponding to the numbers on the check sent with the package, and the voucher or check retained by the cashier, and the check sent with the package. Three separate tearing operations are

involved in each transaction of even the simplest sort when this form of book is used.

The object of this invention is to overcome the objections incident to books now in use, which I do by so making the book and arranging the intelligence thereon, that a single writing operation and a single tearing operation will suffice to do efficiently and in an entirely satisfactory manner all of the things required or involved in the manifold and useless operations above detailed. I have found in actual practice that with the use of a book constructed in accordance with this invention, the necessary transactions incident to a cash sale can be performed in less than a third of the time required with the old books and methods and in a much neater and more cleanly way since it obviates the use of the carbon sheet which soils or smuts the hands of the clerk, and the book.

A further object of the invention is to provide a book in which the voucher and check designations will be ascertainable at a glance, and means for designating accurately the last of the series of vouchers to aid the clerk in gathering together or grasping quickly the necessary number of vouchers in a series and further to provide a means for greatly facilitating in accurately separating the vouchers evenly, and without tearing or mutilating vouchers not intended to be removed, as is the case where near perforations are relied upon as lines of weakness upon which the vouchers are torn apart.

Referring to the drawings,

Figure 1 is a series of plan views representing two voucher sheets and a customers's check sheet;

Figure 2 is a perspective view of one of the sheets of the book with a portion turned back showing the manner of placing the carbon transfer coating upon the sheets.

As has been suggested in the usual transaction of cash sales in large establishments, two vouchers are necessary, a cashier's voucher, a clerk's voucher and a customer's check, the two former being retained in different departments of the store, while the third, the customer's check is placed in the package of merchandise, but I desire it understood that in cases where only two vouchers are needed the construction and arrangement shown would be equally applicable.

Referring to the drawings, the numerals 1, 2 and 3 respectively designate the cash-

ier's voucher, clerk's voucher and customer's check sheets. They are identical in rulings and designations with the exception of the three designations mentioned, namely cashier's and clerk's voucher, and customer's check. Each voucher is provided with a space 4 at one side for the voucher number and letter designation, the voucher number being the same throughout, whereas each 10 voucher is as shown designated by the letters A and B, which have a fixed relation to the voucher number. To the right of the space 4 the vouchers are ruled with parallel rulings indicated by the numeral 5, in which 15 the intelligence "Am't received", and "Section and clerk No." appear, and below the words "Am't received" spaces are provided for the amount in dollars and cents, and below the words "Section and clerk No." is 20 placed the number of the section and clerk, in the present instance 33. Below these spaces are arranged a series of horizontal and vertical rulings, which form spaces 7 for the quantity of articles sold; 8 for the items 25 by name; 9 the price per article, and 10 the total amount of the sale, and below the words "Items" is placed the name of the particular department in which the book is used, in the present instance "Notions".

30 While in the drawings, I have shown samples of but two clerk's vouchers and two customer's checks, lettered A and B, these views only represent a portion of a sheet for in the arrangement of a book, I prefer to 35 make each voucher sheet consist of four vouchers and each customer's check sheet consist of four customer's checks, lettered in the actual book from A to D, inclusive. I also prefer to sever the sheets between the 40 vouchers and checks for a greater portion of their length, as indicated by the numeral 11, the remainder or left side of the vouchers and checks being held together by perforated section 12. It will be noted that the third 45 sheet instead of having designations as "Cashier's voucher" and "Clerk's voucher", has the designation "Customer's check", in the space 4. Otherwise the sheets are identical.

50 The sheets 1 and 2 are provided on their backs opposite the spaces or places where writings are to be made with carbon surfaces 55 but the back of the third or customer's check is not provided with carbon or transfer material but is, on the other hand, provided with some designation, in the present instance a name of a firm, which is fanciful, but serves the purpose of indicating to the clerk the last of the series of vouchers and 60 check so that the requisite number of vouchers and checks may be readily grasped preparatory to the tearing or separating operation.

65 The vouchers are used from the bottom toward the top of the book and the designa-

tion referred to on the back of the customer's check is repeated upon each check so that the indication for aiding the clerk will appear at all times throughout the detaching operation of all of the vouchers.

70 Each series of vouchers and checks bears the same number, as for instance the number 32 as shown, but the succeeding series on the succeeding sheets will bear a progressive number or 33 and so on, which numbers may 75 serve as check and voucher identifications in other connection, as for instance where a delivery sheet is employed in connection with the sales vouchers and checks which delivery sheet may have numbers corresponding 80 to the voucher and check numbers under which reference may be made to the particular voucher and check.

85 In use the clerk fills in the voucher with the amount received, quantity, items, price per item, and the amount of the sale, which writing is transferred to the carbon to the second and third sheets, thus producing a duplicate of the cashier's voucher which duplicates become a clerk's voucher and a customer's check. The clerk then gathers together the vouchers and check and by a very simple operation aided greatly by the severance of the sheets for a portion of their width and by the designation which appears upon 95 the backs of the customer's checks, is enabled to tear off all three of the sections at one time and with a very simple operation. The cashier's voucher is sent with the cash received to the cashier, the clerk's voucher is retained 100 by the clerk and the customer's check is placed in the package, either wrapped up and handed to the customer forthwith or delivered as the exigencies of the case may require.

105 Thus it will be seen that the cashier has at all times a check upon the clerk and the transaction can be readily identified from the customer's check should anything go wrong with the purchase.

110 I do not desire to be understood as limiting myself in any way to the particular forms of rulings or the headings for the rulings as obviously these may to some extent be changed as the exigencies of the case may 115 require.

Having thus described my invention, what I claim is:—

120 1. A sales book comprising in combination, a plurality of sets of leaves each set comprising multiple leaves, the leaves of each set being divided by scorings permitting easy detachment into a plurality of slips, the slips of each leaf of the set being of corresponding number, and corresponding 125 slips of each leaf of the set being arranged to relate to one sales transaction, the different slips being provided with rulings and legends indicating suitable data to be inserted, the slips of each set also having voucher 130

and check designations and being serially marked successively from the bottom to the top of each sheet, a portion of the back of the uppermost slips of each set being coated 5 with transfer material.

2. A sales book comprising in combination a plurality of sets of leaves, each set comprising multiple leaves, the leaves of each set being divided by scorings permitting 10 easy detachment into a plurality of slips, the slips of each leaf of the set being of corresponding number, and corresponding slips of each leaf of the set being arranged to relate to one sales transaction, the different slips being provided with rulings and 15 legends indicating suitable data to be in-

serted, the slips of each set also having a voucher and check designations and being serially marked successively from the bottom to the top of each sheet, a portion of the back of the uppermost slips of each set being coated with transfer material, the back of each slip of the lower sheet of each set being provided with an imprint for the purpose described. 20 25

In testimony whereof I affix my signature in presence of two witnesses.

GEORGE HARTRICK.
